UNITED STATES PATENT OFFICE.

RICHARD BRADSHAW, OF TORONTO, ONTARIO, CANADA.

SPRING-MATTRESS.

1,103,028.

Specification of Letters Patent. Patented July 14, 1914.

Application filed January 30, 1914. Serial No. 815,429.

To all whom it may concern:

Be it known that I, RICHARD BRADSHAW, of the city of Toronto, in the county of York, in the Province of Ontario, Canada, 5 have invented certain new and useful Improvements in Spring-Mattresses, of which the following is the specification.

My invention relates to improvements in spring mattresses and the object of the invention is to devise means whereby each half 10 of the mattress will be independent of the other half so as to prevent the uneven sagging of the mattress due to a heavier weight being on one side than on the other and yet 15 at the same time will present an even supporting surface from one side of the mattress to the other and it consists essentially of a pair of spring mattress sections resiliently supported on suitable side bars and 20 spaced apart centrally of the mattress, a spring bar extending longitudinally between the mattress sections, resilient connecting means between each side of the spring bar and each side of the mattress sections and resilient connecting means between the ends of 25 the spring bar and the mattress frame as hereinafter more particularly explained by the following specification.

Figure 1, is a perspective view of my mattress. Fig. 2, is a cross sectional view through Fig. 1.

In the drawings like letters of reference indicate corresponding parts in each figure.

A is the mattress frame.

35 B and B' are spring mattress sections constructed in the usual manner with end bars B² to which the webbing forming the body of the spring mattress is connected and side wires B³ connected at their ends to the end 40 bars B².

B⁴ are tension springs connecting each end of each mattress section to the bars A.

C is a bar located in the intervening space between the mattress sections and extending 45 centrally therebetween and at their ends into proximity with the bed frame.

C' is a series of tension springs connecting one side of the spring bar to the mattress section B' and C² is an opposing set of tension springs connecting the other side of the 50 spring bar C to the mattress section B.

C³ are tension springs connecting the ends of the spring bar C to the bed frame. By this means it will be readily seen that should the mattress support a heavier weight on 55 one side than on the other that such side supporting the heavy weight will sink independently of the other side, the tension spring C² giving to the required extent to allow of such independent movement. The 60 spring bar C serves to support the ordinary mattress so that there will be no danger of its sinking in the middle as would otherwise be the case if the tension springs extended completely across from one mattress section 65 to the other.

Although I show my construction as applied to a woven wire mattress it will, of course, be understood that it may be equally well applied to other forms of mattress such 70 as a link bar spring mattress or an upholstered spring mattress.

What I claim as my invention is—

1. In a spring mattress, the combination with the main frame, of a pair of independent spring mattress sections resiliently supported at their ends in the main frame and spaced apart, a resilient bar extending longitudinally and centrally between the mattress sections and connecting means between the ends of the bar and the main frame, and tension springs connected to each side of the resilient bar and to the inner side of each mattress section, as and for the purpose specified. 85

2. In a spring mattress, the combination with the main frame, of a pair of mattress sections resiliently supported at their ends in the main frame and suitably spaced apart, a spring bar extending longitudinally and 90 centrally between the mattress sections, tension springs connecting the ends of the spring bar to the main frame and tension springs connecting each side of the spring bar to the inner sides of the mattress section, 95 as and for the purpose specified.

RICHARD BRADSHAW.
